(57) **CLAIM**

The ornamental design for a handle grip as shown and described.

DESCRIPTION

FIG. 1 is a front perspective view of a first embodiment of the handle grip;

FIG. 2 is a front view of the first embodiment of the handle grip (both the front and back views being identical);

FIG. 3 is a right-side view of the first embodiment of the handle grip (both the right and left side views being identical);

FIG. 4 is a top view of the first embodiment of the handle grip;

FIG. 5 is a bottom view of the first embodiment of the handle grip;

FIG. 6 is a front perspective view of a second embodiment of the handle grip;

FIG. 7 is a front view of the second embodiment of the handle grip (both the front and back views being identical);

FIG. 8 is a right-side view of the second embodiment of the handle grip (both the right and left side views being identical);

FIG. 9 is a top view of the second embodiment of the handle grip; and,

FIG. 10 is a bottom view of the second embodiment of the handle grip.

The broken lines depict portions of the handle grip that form no part of the claimed design. The dot-dash broken lines depict boundaries; each dot-dash line and the area within form no part of the claimed design.

1 Claim, 6 Drawing Sheets
